MERCURY STEP SWITCH FOR ELECTRICAL MACHINES AND APPARATUS.

1,426,875.

Specification of Letters Patent. Patented Aug. 22, 1922.

Application filed November 29, 1920. Serial No. 427,121.

To all whom it may concern:

Be it known that I, KARL KAISSER, engineer, a citizen of the Netherlands, and resident of Amsterdam, 139 Sarphatistraat, 5 Netherlands, at present residing at Munich, Seitzstrasse 5/3, Bavaria, Germany, have invented certain new and useful Improvements in Mercury Step Switches for Electrical Machines and Apparatus, of which 10 the following is a specification.

The present invention relates to step or time switches for automatically cutting electrical apparatus in and out of circuit at pre-determined intervals, and it relates more 15 particularly to a switch of this character in which the contact medium—mercury or another suitable fluid electrical conductor—operates alternately within two oscillatably supported concentric chambers in the manner hereinafter described, whereby switching periods of practically absolute uniformity are obtained, which is of the greatest importance in many branches of the art, where exact observation of the continuously succeeding switching operations is imperative. 20

In order to make my invention readily understood, I will now describe it in connection with the accompanying drawing which shows a preferred embodiment in longitudinal section.

The device essentially comprises the tubular metal casing *a* with a barrel-shaped middle portion *e* of somewhat larger diameter than that of the opposed leg portions. 35 This casing is oscillatably suspended by the yoke member *b* at the intersection of the longitudinal and vertical middle planes and its weight is so distributed that the device normally balances about its pivot. In the 40 left leg of the casing are adjustably disposed in parallel alignment a plurality of contact members or terminals, whose feet extend into an inner tube or contact chamber *d*. The latter is preferably concentrically nested 45 within the outer chamber *a* and its mouth terminates near the point of suspension of the latter, as clearly shown in the drawing. The right leg of the casing is solid to 50 counterbalance the other leg with the exception of a small chamber communicating with the barrel portion *e*, the two together serving as a reservoir for the body of mercury *f*. Between the lower walls of the two nested chambers *a* and *d* there is provided

a passage *g*, of relatively small cross-section, 55 and a port *h* admits of communication between this passage *g* and the outer lower end of the inner chamber *d*, an adjustable screw *k*, acting as a valve or stop, controlling the port. 60

The outer left end of the titable casing *a* carries an adjustable contact member *l*, for instance a carbon brush, adapted to co-operate with the stationary contact member *m*. 65

The operation of the described device is the following: In the inoperative position the tilting member assumes the position shown in full lines, with the left end up and the two contacts *l* and *m* disconnected. In 70 this position the predetermined body of mercury will be found entirely in the bottom of the barrel *e* and the communicating chamber in the right casing leg, with the mercury level just below the mouth of the contact chamber *d*. Upon the device being tilted into the operative (dotted-line) position by any suitable means, such as electromagnets, pressure devices, or the like, not shown here as forming no part of the invention and well known in the art, the two contacts *l* and *m* are conductively connected and the mercury flows into the narrow passage *g* and through the port *h* into the contact chamber *d*, the velocity of its passage being 75 readily controlled by the screw *k*. During the rise of the mercury level in the tube *d*, the contact members *c* are successively submerged and the several circuits served by the individual contacts are correspondingly 80 closed.

Owing to the fact that the reservoir *e* is extended beyond the fulcrum of the device, which fulcrum as described is situate approximately in the center of the casing, the 85 pressure difference between high and low mercury level is practically negligible, so that the mercury level will rise in the contact chamber at an even, uniform rate, resulting in correspondingly uniform switching-on periods.

Upon the device being tilted back into the inoperative position, the mercury is rapidly, practically instantaneously evacuated from the contact chamber into the reservoir, when 105 the device is immediately ready for the succeeding operation.

The design of the parts and the amount

of mercury are such that the latter can never enter the contact chamber through its mouth, but solely through the passage *g* and port *h*, no matter what the position of the device 5 relative to its fixed suspension member *b*.

What I claim is:—

1. In an electric time switch of the character set forth, in combination, an outer chamber serving as a reservoir for a fluid 10 electrical conductor, a contact chamber of approximately half the length of said outer chamber and nested therein, a passage of relatively narrow cross-section between the said two chambers and means in said passage 15 for controlling the flow of said fluid conductor therethrough, contact members extending into said inner chamber, means for vertically tiltably suspending said nested chambers, and circuit closing means adapted 20 to be operated by the tilting of the device.
2. In an electric time switch of the character set forth, in combination, a casing comprising two opposed legs and a central barrel portion adapted to contain a body 25 of mercury, and means for vertically tiltably suspending said casing at about the intersection of its longitudinal and vertical middle planes, a contact chamber nested in said casing and occupying 30 one leg thereof and extending approximately halfway into said barrel portion thereof, a passage between said barrel portion and the outer end of said contact chamber, throttling means interposed in said passage for 35 controlling the flow of mercury therethrough from said barrel portion to said contact

chamber, contact members extending into said contact chamber in substantially parallel alinement, and circuit closing means adapted to be operated by the tilting of the 40 device.

3. In an electric time switch of the character set forth, in combination, a casing comprising a middle barrel portion, a hollow left leg and a partly hollow right leg, said 45 barrel portion and said right leg normally holding a body of mercury, means for vertically tiltably suspending said casing at about the intersection of its longitudinal and vertical middle planes, a contact chamber arranged in said hollow left leg of the casing and extending into said barrel portion thereof to approximately the point of suspension thereof, the amount of mercury being such that in any relative position of 50 the device the mercury level extends below the lower lip of the mouth of said contact chamber, contact members in said contact chamber, a passage connecting said barrel portion with the lower outer end of said 55 contact chamber, an adjustable flow-controlling means in said passage, and circuit closing means adapted to be operated by the tilting of the device.

In testimony whereof I have hereunto 65 signed my name this 27 day of October 1920, in the presence of two subscribing witnesses.

KARL KAISSER.
